UNITED STATES PATENT OFFICE.

ERIC SWENSSON, OF CHICAGO, ILLINOIS.

ERASER.

SPECIFICATION forming part of Letters Patent No. 699,934, dated May 13, 1902.

Application filed February 17, 1902. Serial No. 94,555. (No model.)

To all whom it may concern:

Be it known that I, ERIC SWENSSON, of Chicago, in the county of Cook and State of Illinois, have invented certain new and useful 5 Improvements in Erasers, of which the following is a full, clear, and exact description, reference being had to the accompanying drawings, forming a part of this specification, in which corresponding letters of reference in 10 the different figures indicate like parts.

The object of my invention is to provide an eraser for the use of draftsmen, bookkeepers, type-writers, and others having occasion to erase ink or pencil marks, which device may 15 be so constructed as to enable its work to be done with speed and accuracy, while the soiling of the surface from which the erasure is made may be avoided, all of which is herein-after more particularly described, and definitely pointed out in the claims.

In the drawings, Figure 1 is a side view of my improved device. Fig. 2 is a plan view thereof, showing the tubular handle in section. Fig. 3 is an enlarged central longitudinal sec- 25 tional view in detail of a portion of the tubular handle, and Fig. 4 is an edge view in detail of the eraser and hub upon which it is mounted.

Referring to the drawings, *a* represents a 30 hollow metal tube forming the handle of my improved eraser, upon one end of which is brazed or otherwise formed a bifurcated extension *b*, between the branches of which is interposed a hub *c*, which is journaled in a 35 suitable bearing preferably formed by inserting a pin *d* through the axis of said hub and through bores in the ends of said branches.

Mounted upon the hub *d* midway between its ends is an erasing-disk *e* of any suitable 40 erasing or abrading material, such as india-rubber or rubber and other composition employed for erasing purposes.

Upon the hub *c*, and preferably upon opposite sides of the disk *e*, are formed grooved 45 pulleys *f*, upon which a cord *g* is wound and extended into the tube *a*, as shown in Fig. 2, where the ends are attached at *h* to one end of a spiral spring *i*, the other end of said spring being attached to a screw-plug *j*, which 50 is tapped into the end of the tube *a*. The ends of said cord are so attached to the spring as to cause the parts to be separated from but

parallel with each other, so as not to rub against the disk *e* when the latter is rotated. I prefer to attach a metal clip *k* to the cord 55 near the outer end or loop, which clip serves to separate the parts thereof, as shown, and to form a stop for the purpose hereinafter stated. To the outer end or loop of said cord I attach a handle *l*, consisting, preferably, of 60 a wire bent in the manner shown in Fig. 1.

The operation of my improved device is as follows: The spring *i*, being under constant tension, acts to draw the cord *g* into the tube until the stop *k* is in engagement with the 65 disk *e*, as indicated in Figs. 1 and 2, which is the normal position of said stop. The handle *a* is grasped by the user in one hand and the periphery of the disk held against the surface to be erased. The handle *l* is then grasped 70 by the other hand and the cord drawn out to its full length, which movement, by the action of the cord upon the pulleys *f*, serves to rapidly rotate the disk. When the limit of outward movement is reached, the strain upon 75 the cord is relaxed and the recoil of the spring acts to reverse the movement of the cords, thereby causing the disk to rotate in an opposite direction. This reciprocating action of the hand causes the disk to rotate back 80 and forth with considerable speed, while at the same time the position of the disk may be changed by the user until the work is finished.

My improved device enables erasing to be 85 done with speed and neatness and is especially applicable to draftsmen's use. In order to render said device more effectual for said purpose, I prefer to attach to the opposite end of the handle from that upon which the 90 disk is mounted a brush *m*, the bristles of which are preferably secured in a bore formed in the plug *J*. The advantage of this appliance is obvious.

It is manifest that a rubber cord or any 95 well-known elastic material may be substituted for the spring *i*, and when I use the word "spring" in the claims I mean any suitable elastic material, nor do I confine myself to the location of the spring, although I prefer to use it within a tubular handle.

Having thus described my invention, I claim—

1. An eraser in which is combined a handle,

- a revolute erasing-disk mounted in a bearing at one end thereof, the axis of which is arranged at right angles to that of said handle, a spring secured to the opposite end of 5 said handle, a pulley upon the axis of said disk and a cord trained over said pulley, one end of which is attached to said spring, and the other of which is free to be grasped by the hand.
- 10 2. An eraser in which is combined a tubular handle, a revolute erasing-disk mounted thereon, a spiral spring within said handle,

cords having their ends attached to said spring said cords being trained over pulleys upon opposite sides of said disk, and a handle attached to the opposite ends of said cords, substantially as and for the purpose specified.

In testimony whereof I have signed this specification, in the presence of two subscribing witnesses, this 15th day of February, 1902. 20
ERIC SWENSSON.
